UNITED STATES PATENT OFFICE.

GEORGE H. GILMAN, OF BELMONT, MASSACHUSETTS.

DRILLING MACHINE.

Application filed January 11, 1923. Serial No. 611,976.

My invention pertains to fluid pressure motors and relates particularly but not exclusively to drilling machines and especially to machines for drilling rock.

5 My invention will be best understood from the following description when read in the light of the accompanying drawings of a specific embodiment of my invention selected for illustrative purposes, while the scope of 10 my invention will be more particularly pointed out in the appended claims.

In the drawings:—

Fig. 1 represents a longitudinal section of a rock drill embodying my invention;

15 Fig. 2 is a section on the line 2—2 of Fig. 1 of the rearward portion of the rock drill; Figs. 3 and 4 respectively are sections on the lines 3—3 and 4—4 of Fig. 1;

20 Fig. 5 is a section on the line 5—5 of Fig. 1 with the parts moved to another position for convenience of illustration;

Figs. 6, 7 and 8 are sections corresponding to Fig. 5 with the parts moved into different positions;

25 Fig. 9 is a section on the line 9—9 of Fig. 2; and

Figs. 10 and 11 respectively are sections of the inner motor member on the lines 10—10 and 11—11 of Fig. 5.

30 Referring to the drawings I have shown a drill steel 1 the shank 3 of which is mounted in the chuck 5 in such manner that when the chuck rotates the drill steel must rotate with it. Rearwardly of the drill steel 35 I provide a reciprocatory hammer piston which herein comprises the head 7, the forward extension 9, and the rearward extension 11, the forward extension as shown being adapted to strike the end of the shank 40 of the drill steel at the end of the forward stroke of the piston and the rearward extension as shown being provided with the reduced diameter portion 12 near its junction with the head.

45 The chuck and hammer piston are mounted in a casing 13 which is provided with a bore 15 for receiving the chuck and extension 9 of the piston, a bore 17 for receiving the extension 9 of the piston, a bore 19 for receiving the head 7 of the piston, and a bore 21 for receiving the extension 11 of the piston.

50 As is best shown in Fig. 2 the casing illustrated includes a section 23 which abuts the

section having the bore 19, the section 23 being provided with a bore 25 in which is 55 permanently secured the section 27 of the casing, the latter section having the bore 21. At the rearward side of the section 23 the section 27 is provided with an exterior flange 60 29. Rearwardly of the flange the exterior portion of the section 27 is squared as is 65 illustrated in Fig. 4. Rearwardly of the squared portion the section 27 is provided with a cylindrical portion 30 of reduced 70 diameter so as to form a shoulder 31, and is further reduced in diameter as indicated at 75 33 to afford the shoulder 35.

Upon the exterior of the portion of the 70 section 27 received in the bore 25 of the section 23 are shown annular grooves 37, 39 and 41. With the groove 41 communicates the motive fluid supply passage 43 formed in the section 23 and leading from the motive fluid supply connection 45, the passage being controlled by the throttle valve 47. Connecting the groove 41 with the bore 21 are the radial 75 passages 49. Leading rearwardly from the radial passages 49 are the grooves 51 formed on the interior surface of the bore 21. Leading 80 rearwardly from the passages 49 in such position as to intersect the grooves 51 are the passages 53 which open into the bore 21 at its extreme rearward end by way of the annular groove 55 formed as an enlargement 85 of the bore 21 and intersecting the passages 53. Placing the groove 39 in communication with the bore 21 are the radial 90 passages 57, and leading from the groove 39 to the forward end of the bore 19 are the passages 59. At the central portion of the bore 19 is formed an enlargement 61 which is 95 placed in communication with the exhaust nozzle 63 of the machine by a passage 65.

When the throttle valve 47 is placed in the 95 position shown by Fig. 2 motive fluid may pass from the source of the motive fluid supply to the groove 41, whence it passes by means of the grooves 51, passages 53 and groove 55 to the rearward end of the bore 100 21 so as to maintain a continuous pressure on the rearward end of the piston extension 11. With the parts in the position shown by Figs. 1 and 2 motive fluid will pass from the rearward end of the bore 21 and from 105 the passages 49 to the forward end of the bore 19 by way of the passages 57, groove 39 and passages 59. The rearward side of the head

7 at this time uncovers the enlargement 61, and as a consequence the piston moves rearwardly. When it reaches the rearward portion of its stroke the reduced portion 12 of 5 the extension 11 establishes communication between the passages 49 and the rearward end of the bore 19, and as at this time the forward side of the head 7 has opened the forward end of the bore 19 to the enlargement 10 61 the piston moves forwardly under the influence of pressure acting upon the rearward side of the head 7 and upon the rearward end of the extension 11.

As the specific details of the piston and 15 means for causing it to reciprocate do not form part of my present invention the same will not be further described.

As is best shown by Fig. 5 the squared portion of the member 27 lying between the 20 flange 29 and shoulder 31 provides oppositely disposed flat surfaces 67. Mounted for reciprocation upon these flat surfaces is shown the ring like motor member 69 which surrounds the casing section 27. Surrounding the ring like member is shown a second motor member or yoke 71 which has interior flat sides 73 at right angles to the flat sides 67, so that the member 71 may reciprocate upon the member 69. The member 71 herein 30 is supported upon eccentrics 75 which are carried upon rotatable shafts 77 positioned in the same plane equidistant from the axis of the piston and chuck. It will be thus noted that if the eccentrics rotate in phase the 35 member 71 will partake of an orbital movement about the axis of the piston and chuck, the diameter of the orbit being equal to twice the eccentricity of the eccentrics.

Herein, as best shown in Fig. 2, about the 40 motor members 69 and 71, I place the casing section 79 which has an interior flange 81 fitting the periphery of the flange 29 of the casing section 27 both flanges being of the same thickness. Upon the portion 30 of the 45 casing section 27, I place the casing section 82. The rearward sides of the motor members 69 and 71 bear against the forward face 83 of the casing section 81, while the motor member 69 is provided with a flange 50 85 which bears against the rearward faces 89 of the flanges 81 and 29. The motor member 71 is of such dimension that it fits the wall 83 and the rearward face of the flange 85.

As is best shown in Figs. 1 and 4, herein 55 the flange 81 of the casing section 79 is bored out to receive the bearing blocks 91 which are flattened as indicated at 93 in Fig. 4 to fit the flattened portions 95 of the flange 29. 60 Thus the bearing block is prevented from rotating and serves to dowel the parts together. The flanges 85 of the member 69 serve to prevent motive fluid from leaking out of the spaces between the motor members around 65 the joints between the flanges 81 and 29 and

bearing blocks 91 when said motive fluid is admitted to operate the motor member in a manner hereinafter described.

As illustrated, upon the portion 30 of the casing section 27 is rotatably mounted the 70 gear 97, best shown in Fig. 9, and in mesh therewith are the gears 99 carried by the shafts 77, the gears 97 and 99 causing the shafts to rotate in unison. The casing section 82 is recessed to receive the gears as 75 is indicated at 100 in Fig. 9. Mounted upon the portion 33 of the casing section 27 is the sleeve-like section 101 of the casing, the section 101 having a flange 103 which is received in a recess 105 in the casing section 80 82 to cause the section 101 to close the recess 100. Mounted upon and permanently secured to the section 101 is the casing section 107 which is provided with the interior annular groove 109. The section 85 101 and casing section 107 are held in position by the plug 110 which is screw threadedly received in the socket 111 formed in the rearward end of the casing section 27. The plug 110 serves to hold the casing sections 90 79, 82 and 107, and consequently the motor, in assembled relation upon the casing sections 23 and 27 which are permanently secured to each other, so that the motor may be removed as a unit from the rest 95 of the machine, the shafts 77 for this purpose being in two sections detachably splined together as is indicated at 112 in Fig. 1 which figure shows one section provided with an end of square cross-section fitting 100 into a socket of similar cross-section in the adjacent end of the other section. All the parts are held in assembled relation by means of the four side bolts 113.

The groove 109 is shown as connected 105 with a source of motive fluid supply by way of the passage 115 which is controlled by the throttle valve 117. As illustrated by Figs. 2 and 9, from the passage 115 between the throttle valve and groove 109 110 leads a plurality of similar passages 119 which conduct motive fluid to the face 83 of the section 82. Leading from the groove 109 is a second set of passages 121 opening on the face 83. In the motor member 115 71 are provided passages 123 and 125 which respectively connect the rearward face of said member to the upper and lower sides of the interior of said member as viewed in Fig. 2. As indicated by Figs. 2 and 5 the pair of sets of passages 121 and 125 and pair of sets of passages 119 and 121 are adapted to be brought into communication by the upward and downward movement 120 of the motor member 71. This will alternately supply motive fluid to the upper and lower spaces between the motor members 69 and 71, and therefore will cause the motor member 71 to reciprocate relatively 125 to the member 69. As viewed in Fig. 5 130

the passages 121 and 125 are in communication, and this will cause downward movement of the motor member 71. When the motor member 71 approaches the extreme 5 downward limit of its stroke the passage 123 is brought into communication with the passage 119, and this admits motive fluid to cause the motor member 71 to travel to the upper limit of its stroke.

10 For exhausting the motive fluid admitted to the spaces between the motor members 69 and 71 the latter herein is provided with the passages 127 which connect the interior of said member to the interior of the casing 79. The motor member 69 is provided at its corners with notches 128 which are alternately overrun by the inner ends of the passages 127 as the motor member reciprocates relatively to the motor member 69.

15 In the position of parts shown by Fig. 5 the upper passage 127 is in communication with the upper notch 128 and consequently the upper space is exhausted, and with the parts moved to the position shown by Fig. 25 7 the lower passage 127 is in communication with the lower notch 128 and consequently the lower space is exhausted.

For admitting motive fluid to the spaces between the casing section 27 and the motor member 69 I herein provide a passage 129 which opens into the groove 109 by means of an intersecting passage 131 and has connected therewith a passage 133 opening on the lower flat side 67 of the casing member 27 as viewed in Fig. 5. As shown by Figs. 5 and 11 the surface of the motor member 69 in contact with the upper surface 67 as viewed in Fig. 5 is provided with grooves 135 which are adapted to alternately establish communication between the passage 133 and the spaces between the casing section 27 and the motor member 69. In the position of parts shown by Fig. 6 the left hand space is supplied with motive fluid, and in the position shown by Fig. 8 the right hand space is supplied with motive fluid. For controlling the exhaust of the motive fluid acting to reciprocate the motor member 69 I provide a passage 137 which establishes communication between the groove 37 and the passage 139 opening on the upper flat side 67 of the casing section 27 as viewed in Fig. 5. Opposite the passage 69 the motor member 9 is provided with the grooves 141 which have the offset portions 143 adapted when the motor member 69 is reciprocated to be alternately brought into registry with the end of the passage 139. With the parts in the position shown by Fig. 6 the right hand space is connected to the passage 139, and when moved to the position shown by Fig. 8 the left hand space is connected to this passage. The groove 37 is placed in communication with the atmosphere by way of

a passage 145 communicating with the exhaust nozzle 63. Also the interior of the casing section 79 is vented by means of a passage 146 in communication with the groove 37.

The shafts 77 as shown at their forward ends have integrally formed therewith the oppositely disposed eccentrics 147. Upon the similarly disposed eccentrics are mounted yokes 149, the latter being provided with internal gear teeth 151 to mesh with gear teeth 155 upon the chuck. It will be understood by this that the orbital motion of the member 71 is imparted to the shafts which in turn impart the motion to the chuck through the reduction gearing afforded by the yokes 149 in mesh with the chuck. Although the eccentrics 147 for driving the yoke may be of the same eccentricity as the eccentrics 75 associated with the motor, preferably those for driving the yoke are of smaller eccentricity, which enables the provision of a powerful and more efficient motor while maintaining a large gear reduction.

Although I have described for purposes of illustration one specific embodiment of my invention it is to be understood that within the scope of my invention wide deviations may be made therefrom without departing from the spirit of my invention.

Claims:

1. In a rock drill, a chuck formed for carrying a drill steel, a piston for operating said drill steel, a casing for said chuck and piston, said casing having a portion slidably supporting an inner motor member, an outer motor member slidably supported on said inner motor member, means supporting said outer motor member for orbital movement, means for transmitting said orbital movement to said chuck, and means for permitting motive fluid to act upon said motor members for causing said orbital motion.

2. In a rock drill, a chuck formed for carrying a drill steel, a hammer piston for operating said drill steel, said chuck having gear teeth thereon, eccentrics at the side of said chuck, a yoke supported on said eccentrics, said yoke surrounding said chuck and having gear teeth in mesh with said gear teeth of said chuck, other eccentrics aligned with the eccentrics first mentioned and rotating therewith, a motor member supported on said second mentioned eccentrics, and means for permitting motive fluid to act interiorly of said motor member for causing rotation of said eccentrics.

3. In a drilling machine, a chuck, a motor member, means mounting said member for orbital movement and for operatively connecting it to said chuck for rotating the latter, and means permitting motive fluid to act upon said motor member interiorly thereof for causing its orbital movement.

4. In a drilling machine, a chuck, a mo-

tor member mounted for orbital movement about the axis of said chuck and operatively connected to said chuck, and means permitting motive fluid to act upon said motor member interiorly thereof for causing its orbital movement.

5. In a drilling machine, a hammer piston member and a chuck member, the latter formed for carrying a drill steel operated by the former, a motor for driving said chuck, said motor having three substantially annular parts, one of which is stationary and the others of which are movable, one of said movable parts sliding upon the stationary part and the other movable part sliding upon the first mentioned movable part, said parts surrounding one of said members, means for admitting and exhausting motive fluid for actuating said movable parts, means driven by one of said movable parts, said means being connected in driving relation to said chuck and causing said part which drives it to partake of an orbital movement.

20 6. In a drilling machine, a chuck, a casing for said machine, a member surrounding a portion of said casing, means mounting said member for orbital movement, and means permitting motive fluid to act between said member and the portion of the casing which surrounds for giving said member its orbital movement.

25 7. In a drilling machine, a chuck formed for carrying a drill steel, a hammer piston for operating said drill steel, a casing for said hammer piston, a member surrounding a portion of said casing, means mounting said member for orbital movement, means permitting motive fluid to act between said member and the portion of the casing which surrounds for giving said member its orbital movement, said last mentioned means including an inner member slidably mounted on said portion of said casing and said first mentioned member.

40 8. In a rock drill, a chuck formed for carrying a drill steel, a piston for operating said drill steel, a casing for said chuck and piston, said casing having a portion surrounded by and slidably supporting an inner motor member, an outer motor member slidably supported on said inner motor member, means supporting said outer motor member for orbital movement, means for transmitting said orbital movement of said outer motor member to said chuck, and means for permitting motive fluid to act between said motor members for causing said orbital motion.

45 9. In a rock drill, a chuck formed for carrying a drill steel, a piston for operating said drill steel, a casing for said chuck and piston, said casing having a portion surrounded by and slidably supporting an inner motor member, an outer motor member slidably supported on said inner motor

member, means supporting said outer motor member for orbital movement, means for transmitting said orbital movement of said outer motor member to said chuck, and means for permitting motive fluid to act between said casing and inner motor member for causing said orbital motion.

50 10. In a rock drill, a piston having an extension, a chuck formed for carrying a drill steel operated by said piston, a motor surrounding said extension, said motor comprising a stationary member and two movable members all nested together, means supporting one of said movable members for orbital movement, and motion transmitting means independent of said means supporting said member for orbital movement, said reduction gearing including reduction gearing operated by said orbital movement for rotating said chuck.

55 11. In a rock drill, a piston having a rearward extension, a chuck formed for carrying a drill steel operated by said piston, a motor surrounding said extension, said motor comprising a stationary member and two movable members all nested together, said stationary member having a bore forming a cylinder wall for the rearward extension of said piston, means supporting one of said movable members for orbital movement, and motion transmitting means operated by said orbital movement for rotating said chuck.

60 12. In a rock drill, a piston having a rearward extension, a chuck formed for carrying a drill steel operated by said piston, a motor surrounding said extension, said motor comprising a stationary member and two movable members all nested together, means supporting one of said movable members for orbital movement, and motion transmitting means operated by said orbital movement for rotating said chuck.

65 13. In a rock drill, a chuck formed for carrying a drill steel, a hammer piston for operating said drill steel, said hammer piston having a head and a rearward extension, a casing having bores for said chuck and the head and rearward extension of said piston, the portion of said casing having the bore for said rearward extension being formed exteriorly thereof with two oppositely disposed flat sides, a ring surrounding said portion and being slidably mounted upon said flat sides, said ring having flat sides on its exterior disposed transversely to the flat sides of said portion of said casing, a member surrounding said ring and being slidably mounted upon the exterior flat sides of said ring, said last named member being supported upon spaced eccentrics mounted on separate shafts, means for causing said shafts to rotate in unison and for imparting said rotation to said chuck.

14. In a rock drill, a piston having a rearward extension, a casing for said extension having an exterior portion of substantially square cross-section, a ring like member mounted upon said exterior portion of said casing for reciprocation transversely thereto, a second member mounted upon said ring like member for reciprocation transversely to the reciprocation of said 10 ring like member, a chuck, and means operatively connecting said chuck to said second member.
15. In a rock drill, a chuck formed for carrying a drill steel, a piston for operating said drill steel, a casing for said chuck and piston, said casing having a portion surrounded by and slidably supporting an inner motor member, an outer motor member slidably supported on said inner motor 20 member, means supporting said outer motor member for orbital movement, means for transmitting said orbital movement of said outer motor member to said chuck, and ports directly controlled by said members for admitting motive fluid to act upon said members for causing said orbital motion.
16. A fluid pressure motor having a central stationary portion provided exteriorly thereof with oppositely disposed flat sides, a 30 member surrounding said stationary portion and having an interior bearing upon said flat sides, said member having exteriorly thereof oppositely disposed flat sides at right angles to the flat sides of said stationary portion, a second member surrounding said first mentioned member and having an interior bearing upon the exterior flat sides of said first member, means supporting said second member for orbital movement, and means for permitting motive fluid to act upon said members for causing said orbital movement.
17. A fluid pressure motor having a central stationary portion provided exteriorly 45 thereof with oppositely disposed flat sides, a member surrounding said stationary portion and having an interior bearing upon said flat sides, said member having exteriorly thereof oppositely disposed flat sides at right angles to the flat sides of said stationary portion, a second member surrounding said first mentioned member and having an interior bearing upon the exterior flat sides of said first member, eccentrics supporting one of said members, means for causing said eccentrics to rotate in unison, and means permitting motive fluid to act upon said member supported by said eccentrics for causing it to rotate said eccentrics.
18. In a rock drill, a chuck, a casing, a 60 gyratory yoke at the forward end of said casing, a gyratory yoke at the rearward end of said casing, means enforcing conjoint movement of said yokes, a piston having a rearward extension of reduced diameter re-
- ciprocating in said casing through said yoke at the rearward end of said casing, the yoke at the forward end of said casing surrounding said chuck and being geared thereto, and means for permitting motive fluid to act upon the yoke at the rearward end of said casing for causing said conjoint movement.
19. In a rock drill, a piston having a rearward extension of reduced diameter, a chuck, a drill steel carried by said chuck and operated by said piston, a casing for said chuck and piston, the portion of said casing receiving said extension of said piston being exteriorly reduced, a gyratory member surrounding said portion of said casing, means for permitting motive fluid to act upon said gyratory member for operating it, and reduction gearing for transmitting motion of said gyratory member to said chuck.
20. In a drilling machine, a chuck having 35 external gear teeth, a gyratory member surrounding said chuck and having internal gear teeth meshing with the gear teeth on said chuck, a second gyratory member mounted rearwardly of said chuck, means 40 enforcing conjoint movement of said gyratory members, and means for permitting motive fluid to act upon said second gyratory member for causing said conjoint movement.
21. In a drilling machine, a chuck having 50 external gear teeth, a gyratory member surrounding said chuck and having internal gear teeth meshing with the gear teeth on said chuck, a second gyratory member mounted rearwardly of said chuck, a casing 55 for said chuck and both gyratory members, said casing providing an annular chamber having inner and outer walls, said second gyratory member being received in said annular chamber and surrounding said inner 60 wall, means associated with one of said walls and said second gyratory member to form an expansible chamber, and means for admitting motive fluid to and exhausting it from said expansible chamber for operating said 65 second gyratory member.
22. In a rock drill; a chuck; a piston for operating a drill steel carried by said chuck; a motor for rotating said chuck; a shaft for transmitting the motion of said motor to 70 said chuck; a casing for said chuck, piston, motor and shaft, said casing being in sections; and said shaft having sections removably splined to each other for permitting the part of said casing for said motor to be removed from the remainder of said casing without disassembling said motor.
23. In a rock drill, a chuck, a motor comprising nested transversely reciprocating members, an eccentric driven by one of said 75 members, a second eccentric driven by the first mentioned eccentric and being of lesser eccentricity, and a gyratory gear operatively connected to said chuck and driven by said second eccentric.

24. In a rock drill, a chuck, a motor comprising nested transversely reciprocating members, an eccentric driven by one of said members, a shaft carrying said eccentric, an eccentric of lesser eccentricity carried by said shaft, and a gyratory gear in driving relation to said chuck and driven by said eccentric of lesser eccentricity.

25. In a rock drill, a chuck, a motor comprising nested transversely reciprocating

members, a pair of eccentrics driven by one of said members, a shaft for each eccentric of said pair, said shafts each carrying an eccentric of lesser eccentricity, and a gyratory gear in driving relation to said chuck and driven by said eccentrics of lesser eccentricity.

In testimony whereof, I have signed my name to this specification.

GEORGE H. GILMAN.
